GROUND ROD BOND

Frederick G. Ridgers, Hamilton, Ontario, Canada,
assignor to N. Slater Company Limited, Hamilton, Ontario, Canada

Application September 14, 1950, Serial No. 184,773

1 Claim. (Cl. 174—7)

1

This invention relates to electrical grounding devices and has special reference to the devices known as ground rods.

Such devices take the general form of long rods driven into the ground usually at a point some distance from the structure or element which it is desired to maintain in grounded condition, a wire leading from such structure or element and having its lower end connected to the upper end of the rod. Obviously such a rod should be of electrically conductive material but of an economical character.

The connection of the grounding wire to such rods is a field operation and one general manner of making such connection is to place a clamp around the rod which acts either to grip the wire against the rod or to have the wire attached or connected to the clamp. Since it is sometimes the practice to drive the rod to such depth that its upper end is about six inches below the surface any such clamping device and the upper part of the rod are exposed to corrosion and while the rod may have its upper part galvanized yet the zinc itself is subject to oxidation. The conductive connection between the wire and the rod is thus apt to become imperfect.

It is the principal object of the present invention to provide a connection between the ground rod and the grounding wire which will be highly conductive and not subject to such corrosion or oxidation as exists in the present known connections.

Another important object of the present invention is to provide a novel construction of ground rod having highly conductive non-corrosive parts welded thereto for engagement by the grounding wire.

A further object of this invention is to provide a novel form of connection for the grounding wire in which a track or fish plate bolt and a nut are used to hold the parts together.

Still another object is to provide simple means for removing the ground wire while testing the ground rod.

With the above and other objects in view, as will be presently apparent, the invention consists of certain novel arrangements of details and combinations of parts hereinafter fully described, illustrated in the accompanying drawings and particularly claimed.

In the drawings like characters of reference indicate like parts in the several views, and:

Figure 1 is a side elevation of a ground rod constructed in accordance with this invention

2 showing one species of ring used herein in position on the rod.

Figure 2 is a section on the line 2—2 of Figure 1.

5 Figure 3 is a side elevation of the upper end of the rod showing a second ring which may be used herein.

Figure 4 is a section on the line 4—4 of Figure 3.

10 Figure 5 is an enlarged fragmentary section of a form of contact ring adapted to be used in this invention.

15 As shown in the drawings, the present embodiment consists of a rod having a length of several feet and a diameter, say from three-eighths of an inch to one inch. The body 10 of this rod terminates downwardly in a long sharp point 11. The upper end of the rod is forged, as by upsetting, to produce a bulged portion 12 just below the end face of the rod. This portion 12 has a pair of 20 parallel side faces 13 and a bolt hole 14 extends between the faces 13. The faces 13 are preferably spaced a distance equal to the diameter of the rod.

25 On one or both of the faces 13 is mounted a ring 15 of highly conductive metal of corrosion and 30 oxidizing inhibiting material. Each ring 15 is welded as at 16 to the rod metal. The rings 15 may be of solid copper, but stainless steel is found, for the purpose of this invention, to be of sufficiently high electrical conductivity and may be 35 readily welded to the rod. A form of ring is shown in Figure 5 which is stamped from sheet steel 18 whereon a copper face 19 has been rolled during the production of the sheet. While the foregoing materials provide excellent rings for this purpose other materials may be used, the essential features being that the material shall be firmly 40 welded to the rod and that the material shall inhibit corrosion and oxidation tending to injure the welded contact with the rod.

45 In order to secure the wire to a rod constructed as above described a track or fish plate bolt 20 is inserted through the conforming hole 14, here shown as oval, with its head 21 bearing on one ring 15 or, when only one ring is used, on the flat 50 side 13 of the rod itself. The head 21 is preferably a snap or round head. The bolt has a washer 23, preferably of copper, mounted thereon to be urged toward the rod 10 by a nut 24, and the washer is preferably formed to curl about the rod in an embrace above and below the bulge 12 to keep from turning with the nut as the latter is tightened, and further forms a guard and guide for the ground wire. These inturned portions are indicated by 23a. In attaching the wire 25 it is 55 looped and the loop is placed between the washer

23 and the adjacent ring 15. The nut 24 is then tightened up and the wire 25 tightly clamped between the washer 23 and the adjacent ring 15. There is thus provided a permanent but separable connection between the wire 25 and rod 10 and one in which there can be no break in the current conducting path.

Further, it will be observed that the structure herein facilitates detachment of the ground wire from the ground rod for the purpose of running the conventional periodic ground rod resistance tests and again making the connection with the maximum of effective current contact capacity.

In assembling the rod and ring, it is well to first weld the ring to the uncoated rod, then galvanize the assembled rod and ring, and finally remove the zinc from the face of the ring by grinding or otherwise.

What is claimed is:

In combination, a ground rod having a bulged portion adjacent its upper extremity, said bulged portion having a pair of flat parallel sides and having an oval-shaped bolt receiving opening extending between said sides, a ring of material

highly conductive of electricity surrounding each end of said opening and welded thereto, said ring being of material resisting corrosion and oxidation, said ring being formed of composite sheet material having a weldable layer adjacent said rod, and a copper outer layer, and wire securing means including a headed bolt extending through said opening and having a threaded end projecting through one of said rings, said bolt having a nut on said threaded end and a washer interposed between said nut and the adjacent ring, said washer having its ends turned to protect said ring, bolt and opening.
